LAPPING MACHINE

Herbert S. Indge, Westboro, Mass., assignor to
 Norton Company, Worcester, Mass., a corporation of Massachusetts

Application October 30, 1937, Serial No. 171,931

8 Claims. (Cl. 51—50)

The invention relates to lapping machines, and with regard to its more specific features to a lapping attachment which may be incorporated in a cylindrical grinder.

5 One object of the invention is to provide an improved grinding and lapping machine for obtaining a lapped surface on a shaft or cylinder in the same machine which grinds the shaft or cylinder. Another object of the invention is to 10 provide an attachment whereby shafts can be quickly lapped. Another object of the invention is to provide an apparatus and method for the efficient lapping of cylindrical bodies. Another object of the invention is to provide a high speed 15 reciprocating mechanism for the lapping of metal parts involving a minimum of vibration or stresses set up by inertia. Other objects will be in part obvious or in part pointed out hereinafter.

The invention accordingly consists in the features of construction, combinations of elements, arrangements of parts, and in the several steps and relation and order of each of said steps to one or more of the others thereof, all as will be 20 illustratively described herein, and the scope of the application of which will be indicated in the following claims.

In the accompanying drawing in which is illustrated one of many possible embodiments of the mechanical features of this invention,

30 Figure 1 is a front elevation of a grinding machine having the lapping attachment incorporated thereon,

Figure 2 is an enlarged front elevation of the lapping attachment showing the wheels and 35 mounting in axial section, and

Figure 3 is a side elevation on the same scale as Figure 2 of the lapping attachment and its mounting on the wheel head, certain spindles being shown in section.

40 I provide a plain cylindrical shaft grinder of any preferred or desired form. Merely for purposes of illustration, I show in Figure 1 a cylindrical grinder comprising a base 10 supporting on the usual ways for longitudinal reciprocation a table or carriage 11 which carries at one end a headstock 12 and at the other end a tailstock 13. The headstock journals a spindle, not shown, having on one end thereof a driving face plate 14 and a head center 15. By means of the usual lathe dog 16, the shaft 17 to be ground is rotated from the face plate 14. The face plate 14 may be driven by an electric motor 20 having an armature shaft 21 which drives the spindle for the face plate by means of reduction gearing in the head 12, not shown, and a belt or chain drive in the casing 23.

Tailstock 13 may be of any usual or desired construction, it being broken away in Figure 1 more clearly to show the lapping attachment. Both the headstock 12 and the tailstock 13 are adjustable on slideways 25 on the table or carriage 11 in order that the machine may grind different sized shafts 17.

The machine may have the usual wheel head 30, Figure 3, journaling a shaft 31 upon which is mounted a grinding wheel 32, Figure 1. In such event there is preferably provided a motor 33 driving a pulley 34 which is connected by multiple belts 35 to a pulley 36 attached to the shaft 31. The usual cross slideways, not shown, for the wheel head 30 are also provided whereby to move 15 the grinding wheel 32 towards and from the shaft 17.

For control of the cross feed there is provided a hand wheel 40 with a micrometer adjustment device 41 and a ratchet wheel, not shown, operated by a pawl 42 which is attached to a slide 43 operated by a connecting rod 44 eccentrically attached to a disk 45. Connected to the disk 45 is a small gear, not shown, which meshes with a rack on the end of an arm 48 which is connected 25 at 49 to an arm 50 attached to the main reversing lever 51 which is positioned for contact with the usual table reversing dogs or stops 52 and 53 adjustably secured to the table or carriage 11. The reversing lever 51 operates a mechanical reversing 30 mechanism, not shown, to traverse the table 11 first in one direction and then in the other, according to the position of the lever 51. By means of a hand lever 55, the direction of travel of the table 11 can be reversed manually. I provide further manually operated mechanism for moving the table or carriage 11 comprising a hand wheel 60 mounted on a shaft 61 to which is attached a pinion gear 62 meshing with a large gear 63 to which is attached a pinion gear 64 meshing with a rack 65 attached to the under side of the table 35 or carriage 11. For the mechanism thus indicated, hydraulic driving and reversing mechanism may be substituted, if desired. For a fuller description of one form of grinding machine embodying many of the features heretofore indicated, reference may be made to the patent to C. H. Norton No. 762,838 granted June 14, 1904.

45 Referring now to Figure 3, on the wheel head 30 I provide an extension 10 having ways receiving a slide 71 which on its under side has a rack 72 meshing with a pinion 73 controlled by a hand wheel 74 whereby the slide 71 may be moved parallel to the cross slide of the machine. I provide a screw 76 controlled by a hand wheel 77 50 for locking the slide 71 in the desired position of

adjustment. The slide 71 supports the lapping attachment which is more particularly the subject matter of this invention. As shown in Figures 2 and 3, an electric motor 80 of any usual or preferred kind is attached to an angle plate 81 which in turn is secured to the slide 71. The motor 80 has an armature shaft 82 on the front of which is located a face plate 83 with a slot 84 in which is adjustably fastened a stud 85 to which 5 is connected a link 86 secured in place by means of a nut 87. The other end of the link 86 is connected by a pin 88 to levers 89 pivoted on a pin 90 secured to a block 91 attached by means of screw bolts 92 to the angle bracket 81. As shown 10 in Figure 3, an upper block 94 and a lower block 95 are held against the angle bracket 81 by means of clamping plates 96 and 97 respectively which are held in position by bolts 98 and 99. On the under side of the block 94 is a V groove 100 and 15 on the upper side of the block 95 is a V groove 100. On each of the upper and lower sides of the block 91 is a V groove 100.

Still referring to Figures 2 and 3, I provide a pair of slides 101 and 102 which have V grooves 25 103 on their upper and lower surfaces. Bearing balls 104 fit between the respective grooves 100 and 103, as shown in Figure 3. By means of pins 105 and 106 the slides 101 and 102 are connected to the levers 89.

30 It will be seen that as the armature shaft 82 of the motor 80 rotates, the levers 89 will be oscillated and this action will oscillate the slides 101 and 102. The amplitude of oscillation is such that the slight looseness in the connection at the pins 35 105 and 106 will take care of the angular movement of the lever 89 and therefore the slides 101 and 102 are given a true reciprocating motion. The link 86, the lever 89 and the slides 101 are of skeleton construction as shown, having holes 40 therein clearly illustrated in Figure 2 to remove as much weight as possible. I have found that it is possible effectively to reciprocate the slides 101 and 102 twelve hundred complete reciprocations a minute with an amplitude of about a 45 quarter of an inch. Furthermore, this reciprocation takes place without excessive vibration of the entire mechanism supported on the slide 71, since the slides 101 and 102 are always moving oppositely. Friction is reduced to a minimum by 50 means of the bearing balls 104 and inertia is reduced to a minimum by removing as much metal as possible from the various parts, as already pointed out.

Still referring to Figure 2, extending from the 55 left hand end of the slides 101 and 102 respectively are integral spindles 110 upon which are mounted flanged sleeves 111 having flanges 112 and an interposed washer 113 abutting the shoulders 109 which comprise the ends of the slides 60 101 and 102. The left hand ends of the sleeves 111 are threaded and by means of nuts 114 engaging these threaded portions abrasive wheels 115 are secured upon the sleeves 111 to the spindles 110 having reduced threaded portions 116 65 upon which are nuts 117 securing the sleeves 111 in place. The spindles 110 have a reduced diameter cylindrical portion 120 extending from the left hand end thereof upon which are mounted cups 121 keyed to the portions 120. The extreme left hand ends of the spindles 110 are 70 threaded and nuts 122 hold the cups on the portions 120. Inside of the cups 121 are springs 123 exerting their pressure against the cups at one end and against washers 124 at the other 75 end, which washers engage the nuts 114.

It will thus be seen that the abrasive wheels 115 are thrust to the right by the springs 123 and the thrust is taken by the aforesaid shoulders 109. This constitutes friction means preventing free rotation of the abrasive wheels 115. 5

The abrasive wheels 115 may be made of any suitable abrasive such as fused alumina or silicon carbide bonded with any suitable bond such as any one of the clay or resinous bonds, rubber, or any other type. Furthermore for some purposes diamond abrasive may be used. I have found that an excellent finish may be achieved upon a shaft 17 by rapidly reciprocating the wheels 115 which are held from free rotation as described. This produces a lapping action 15 upon the work piece which peens the grooves produced by grinding. The cups and springs may be termed braking means to restrain the rotation of the wheels 115.

In the operation of the machine, the operator 20 may first advance the cross slide and grind the shaft 17 in the usual manner. At this time the slide 71 will be back so that the abrasive wheels 115 will not be in contact with the work piece. When the shaft 17 has been ground, the operator 25 will move the main wheel slide slightly to the rear by means of the hand wheel 40 or micrometer control 41, and then adjust the table 11, as by means of the hand wheel 60, to bring the abrasive wheels 115 opposite the portion of the 30 shaft 17 which was ground. The operator then turns the hand wheel 74 to adjust the wheels 115 into contact with the shaft. In certain embodiments of the invention, the wheels 115 may be made of cast iron or the like and loose abrasive 35 powder may be used to perform the lapping operation. For the lapping a firm contact between the abrasive wheels and the work piece is preferred but not such a pressure as will materially slow down the motor 80. The motor 80 is then 40 energized and operated at an angular velocity of from six hundred to eighteen hundred R. P. M. which causes the wheels 115 to reciprocate at from six to eighteen hundred times a minute, with an amplitude of any amount up to three-eighths of an inch. It should be understood that so far as certain features of the invention are concerned, other rates of reciprocation at other amplitudes may be employed. During the lapping operation, the work piece 17 is rotating in 45 the usual manner, which tends to rotate the wheels 115, but the slight slippage due to the friction against the wheels 115 materially assists in the lapping action. 50

It will thus be seen that there has been provided by this invention an apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be 55 interpreted as illustrative and not in a limiting sense. 60

I claim:

1. A grinding machine comprising a base, a table or carriage mounted on said base, a headstock and tailstock mounted on said carriage, a cross slide, a second slide mounted on said cross slide, and a lapping attachment on said second slide comprising a pair of additional slides mounted to reciprocate, means to reciprocate said 70 75 80 85 90 95 98 99 100 105 110 115 120 125 130 135 140 145 150 155 - last named slides, and a small grinding wheel mounted on each of said last named slides.
2. A high speed lapping attachment comprising a pair of abrasive wheels, spindles mounting said abrasive wheels close together and in parallel relation, said abrasive wheels being free to rotate on said spindles, means retarding the rotation of said wheels on said spindles, a slide for each spindle, said slides being mounted in slide-ways in parallel relation, the slides being of skeleton construction, a skeleton construction lever connected to said slides and pivoted between them whereby as it is oscillated the slides will be reciprocated oppositely, an electric motor, and a skeleton construction link connecting said lever to an operating part of said electric motor.
3. A lapping apparatus comprising a light weight slide, a spindle on said slide, a slideway supporting said slide, a grinding wheel mounted to revolve on said spindle, means retarding the rotation of said grinding wheel, and means to reciprocate said slide rapidly.
4. In apparatus of the class described, a bracket, an electric motor mounted on said bracket, a plate mounted on the armature of said motor, a pin radially adjustable on said plate, a link mounted on said pin, a lever to which said link is connected, a pivot pin on the bracket for the lever, a pair of pins at equal distances above and below said last named pin, a pair of slides mounted in parallel relation, each connected to one of said last named pins, abrasive wheels in coaxial relation mounted on said slides, and means to retard the revolutions of said abrasive wheels.
5. In a grinding machine, means to hold and rotate a generally cylindrical work piece, a grinding wheel to grind said work piece, a pair of lap-
- ping wheels to lap said work piece mounted on axes parallel to each other and parallel to the grinding wheel, means to reciprocate said lapping wheels oppositely, and means retarding rotation of said lapping wheels, whereby all portions of the work piece may be lapped to the same extent by grinding and lapping the work piece without removing it from the holding and rotating means.
6. In a machine of the class described, a pair of grinding wheels, means mounting said grinding wheels on parallel axes, means to reciprocate the grinding wheels axially and oppositely, and means restraining rotation of the grinding wheels, whereby to achieve a fine lapping action on a work piece.
7. An attachment comprising a pair of parallel slideways, a pair of slides mounted in said slideways, bearing balls interposed between the slides and the slideways, reciprocating means for reciprocating the slides oppositely, an abrasive wheel rotatably mounted on each slide, and means to restrain the rotation of each abrasive wheel, whereby to achieve a fine lapping action on a work piece, the lapping lines being broken up by the reciprocation.
8. Method of lapping a work piece which is a surface of revolution which comprises rapidly reciprocating an abrasive wheel in contact with the work piece, the line of reciprocation being parallel to the axis of the work piece, and the abrasive wheel being rotated by its contact with the work piece and retarded from free rotation, thus producing a dragging action on the work piece to effect a fine lapping, the reciprocation breaking up the lapping lines.

HERBERT S. INDGE.
